O. E. OLESON

VALVE

Filed July 20, 1922

OLAF E. OLESON
INVENTOR.

BY

Albert C. Bell
ATTORNEY.

UNITED STATES PATENT OFFICE.

OLAF E. OLESON, OF EAST CHICAGO, INDIANA.

VALVE.

Application filed July 20, 1922. Serial No. 576,175.

To all whom it may concern:

Be it known that I, OLAF E. OLESON, a citizen of the United States, residing at East Chicago, in the county of Lake and State of Indiana, have invented a new and useful Improvement in Valves, of which the following is a specification.

My invention relates to an improved form of valve particularly adapted to control the flow of high pressure steam and consists essentially of a casing containing valve members for controlling the flow of fluid through the valve depending upon whether said members are in engagement or separated from each other, said members being constructed to effectively co-operate with each other during the closing operation so as to first restrict the flow of fluid through the valve and permit the flow of a small quantity of fluid across the seating faces of said members as they approach each other to thoroughly clean said seating faces, flanges being provided to protect the seating faces against the scoring or cutting action of the main flow of the fluid between the members before it is interrupted in part, without, however, interfering with the cleaning action of the members referred to. My present invention is an improvement on the invention shown in United States Letters Patent No. 905,219, which were issued to me December 1, 1908, the particular features of improvement being the provision of the cleaning action of the seating faces just referred to and in addition the disposing of the seating faces in inclined instead of horizontal position which not only better protects the seating faces against the scoring or cutting action of the fluid flow being cut off by bringing the said members together, but also establishes a relation between the seating faces when the members are brought firmly together such that subsequent contraction due to the interruption of the fluid flow holds the seating face of the movable member more tightly against the seating face of the stationary member, which action is most pronounced when the valve is used for controlling the flow of high pressure steam or other fluid at high temperature.

My invention will best be understood by reference to the accompanying drawing showing my valve structure in vertical, central, sectional view and further advantages secured by my improved construction will

appear from the detailed consideration of said drawing.

As shown in the drawing my improved valve construction consists of a valve body or casing 10 having an outlet passage 11 and an inlet passage 12 communicating with each other through the casing when the valve is open. Opposite the passage 12 the casing is provided with an opening to receive the bonnet 13 containing the mechanism for operating the valve structure. The casing has mounted in the inner end of the passageway 12, an externally threaded valve member 14 tightly screwed in place in engagement with corresponding threads in the inner end of the passageway 12 with its axis in line with the operating stem 15 carried by the bonnet 13. The member 14 is annular to permit the flow of fluid therethrough and its inner surface is provided with lugs or grooves 16 to be engaged by a suitable tool for tightly seating the member 14 against the casing 10 or for removing said member when necessary. The member 14 is provided with an inclined or beveled annular valve seat 14^a converging in the direction of the fluid flow and within which radially, an annular groove 14^b is formed which groove as indicated has a rounded bottom and said member carries an upwardly projecting annular flange 14^c which projects somewhat above the valve seat 14^a and which is accurately bored to receive the inner portion of the movable member of the valve structure. The movable valve member of the structure consists of a disk 17 provided with an annular valve seat 17^a of substantially the same diameter as the valve seat 14^a and inclined to accurately fit the valve seat 14^a when the valve is closed. Outside of the valve seat 17^a a depending annular flange 17^b projects from the member 17, said flange being of slightly greater internal diameter than the external diameter of the shouldered portion of the member 14.

The parts are so proportioned that with the member 17 in its closed position, there is a clearance or space between the member 17 and the casing 10 and also between the flange 17^b and the member 14. The lower edge of the flange 17^b is preferably somewhat below the conical surface of the seat 17^a if it were outwardly extended to said flange and between said flange and said seat an annular recess 17^c is formed to insure proper engagement of the seat 17^a with

the seat 14^a and a proper functioning of the flange 17^b to be later described. The member 17 is provided with a central cylindrical flange extension 17^d having an outer diameter slightly less than the diameter of the bore of the flange 14^c and between the cylindrical portion 17^d and the seat 17^a an annular groove 17^e is formed in the member 17 which extends upwardly in said member and 5 is provided preferably with a rounded bottom. The upper portion of the member 17 is provided with a T-shaped slot 17^f to be engaged by the head 15^a on the lower end of the operating stem 15, provided with a 10 lower spherical surface 15^b. The stem 15 passes through a stuffing box 18 carried by the bonnet 13 and above said stuffing box said stem is threaded as indicated at 15^b to engage a similarly threaded member 19 carried by the upper end of the bonnet 13, and outside of the bonnet an operating wheel 20 is secured to the end of the stem 15. Ribs 21 are provided on the inner surface of the casing 10 to engage the outer portion of the 15 movable valve member 17 to guide the latter when it is moved to its closed position. Above the member 17, the stem 15 is provided with a flange 15^d having an upper conical surface for engaging and fitting a 20 similarly shaped chamfer 13^a on the lower end of the bonnet 13 to prevent fluid flow around the stem when repacking the stuffing box 18.

The advantages secured by the above construction and its mode of operation are as follows: When the member 17 is in its uppermost position, a free passage is afforded between the inlet and outlet passages 12 and 11 and for this condition the lower edge 25 of the flange 17^d is well above the upper edge of the flange 14^c so that the fluid may flow without substantial restriction between the valve members and through the bore in the member 14. Bearing in mind that this 30 construction is particularly intended for use in controlling the flow of fluid under high pressure and that the scoring or cutting effect of said fluid is great when forced to rapidly flow through restricted passages, the 35 means I employ in my present structure to avoid cutting the valve seats will be appreciated. During the closing operation of the valve, as the movable member 17 approaches the member 14, the passageway between the 40 edges of the flanges 17^d and 14^c becomes restricted and the velocity of the flow at this point is correspondingly increased. Any 45 cutting or scoring of the flanges 17^d and 14^c which occurs at this time is not detrimental, 50 as said flanges are provided partly for this purpose and it is not essential that the clearance between them shall be any exact amount. The rapidly flowing fluid delivered 55 from between the flanges 17^d and 14^c enters the grooves 17^e and 14^b in which a whirling 60

motion of said fluid is set up and expansion thereof takes place, resulting in dissipating its velocity and energy of flow. At this time, the passageway between the valve seats is still of relatively large cross section and 65 the velocity flow of the expanded fluid across the valve seats is not great enough to do any damage to the valve seats by cutting or scoring. As the member 17 continues to approach the member 14, as a result of the 70 action of the guiding ribs 21, the member 17 is centered relatively to the member 14 and the flange 17^d enters the bore in the flange 14^c thus interrupting the major portion of the flow of the fluid through the valve 75 structure. It has been found impracticable in practice to make the fit between the flanges 17^d and 14^c a tight sliding fit on account of unequal expansion and contraction 80 due to temperature changes, which, particularly when the valve structure is used with high temperature steam, are considerable, the temperature of the valve members being a maximum when the fluid is freely flowing through the valve structure and a 85 minimum when the flow is interrupted by the closing of the valve. I therefore find it advisable to provide a slight clearance between the outer surface of the flange 17^d and the flange 14^c, which clearance is sufficient 90 so that for maximum expansion and contraction of the valve members 14 and 17, there will never be a condition of binding 95 of the flange 17^d in the flange 14^c. As a result, at the time of closing the valve, there 100 is always a certain amount of clearance between the two flanges which although small, is sufficient to permit a perceptible amount of fluid to flow between said flanges and this flow across the valve seats has insufficient 105 velocity to cut or score them but has at the same time sufficient velocity to carry from them any particles of dirt or foreign matter that may have lodged on them and thus when the closing operation is completed, the 110 valve seats are clean and are brought into true engagement with each other to completely interrupt the fluid flow. This true engagement of the valve seats is facilitated by the spherical end 15^b of the rod 15 engaging 115 the bottom of the slot 17^f loosely enough to permit said seating and corresponding necessary movement of the disk 17 relatively to the rod 15 without restraint of any kind by the rod 15.

It will further be observed that the inclined relation of the valve seats produces an accurate centering of the valve member 17 relatively to the valve member 14 when the seats are brought together and furthermore the contraction of the member 17 immediately after the closing of the valve tends to bring the valve seats into more positive engagement than that effected by the turning of the operating wheel 20, which 130

would not be the case were the valve seats or either of them horizontally disposed. Further advantages secured by my construction are that when the valve member 17, 5 during its closing, is still sufficiently above the member 14 to permit rapid flow of the fluid between the valve members, the flange 17^b shields or protects the valve seat 17^a from the action of the rapidly moving fluid 10 and the flange 14^c serves the same purpose for the valve seat 14^a. Furthermore the several grooves and recesses 14^b, 17^c and 17^d serve during the closing operation to direct the rapidly flowing fluid for a brief interval 15 immediately before the flange 17^a enters the flange 14^c, against and across the valve seats which action tends to remove any scale or accumulation that may have formed on or adhered to the valve seats and immediately 20 following this when the flange 17^a has entered the flange 14^c the curved bottoms of the grooves are effective in dissipating the velocity of the fluid still passing between the valve members so that the velocity of 25 the flow across the seats is a minimum. The effect of my construction is thus to momentarily direct the rapidly flowing fluid against and across the valve seats, immediately after which, although the flow is not 30 completely interrupted by the engaging flanges, it is sufficiently reduced in velocity across the valve seats so that it produces no harmful results but has only a cleaning action as it will be observed that before the 35 valve seats engage each other the amount of fluid flow is further reduced on account of the length of overlap of the flanges 14^c and 17^d being at that time a maximum thus affording a maximum resistance to the fluid 40 flow between them. While I have shown the said flanges separated an appreciable distance in the drawing, it will be understood that the amount of clearance between these parts is not as great as represented in 45 the drawing and that the amount of fluid flowing between them immediately before the closed condition of the valve is reached, is not great. It will be also understood that if desired the passageway 12 may be the outlet 50 passageway and the passageway 11 may be the inlet passageway, depending upon the particular conditions of operation and the requirements in any particular case.

While I have shown my invention in the particular embodiment above described it 55 will be understood that I do not limit myself to this exact construction, as I may employ equivalents known to the art at the time of the filing of this application without departing from the scope of the appended 60 claims.

What I claim is:

1. In a valve, the combination of a casing having a passageway through it for fluid flow, coaxial valve members in said casing 65 for closing and opening said passageway, one of said valve members being tubular and fixed and the other of said valve members being disk-like and movable, said valve members having cooperating annular valve 70 seats converging in the direction of fluid flow through the casing, said valve members having cooperating cylindrical flange extensions of smaller diameter than said valve seats and telescopically engaging each other 75 during the closing of the valve to restrict the fluid flow through the casing before said valve seats engage each other, each of said valve members having therein between its flange extension and its valve seat an annular groove having a rounded bottom. 80

2. In a valve, the combination of a casing having a passageway through it for fluid flow, co-axial valve members in said casing for closing and opening said passageway, 85 one of said valve members being tubular and fixed and the other of said valve members being disk-like and movable, said valve members having cooperating annular valve 90 seats converging in the direction of fluid flow through the casing, said valve members having cooperating cylindrical flange extensions of smaller diameter than said valve seats and telescopically engaging each other during the closing of the valve to restrict the fluid flow through the casing before said valve seats engage each other, each of said valve members having therein between its flange extension and its valve seat an annular groove having a rounded bottom, 95 the side walls of one of said grooves being substantially parallel and cylindrical. 100

In witness whereof, I hereunto subscribe my name this 11th day of July, A. D. 1922.

OLAF E. OLESON.
